UNITED STATES PATENT OFFICE.

GEORGE W. GILL, OF THREE RIVERS, MICHIGAN.

OILER FOR THE SLIDES OF WIND MUSICAL INSTRUMENTS.

1,152,407.

Specification of Letters Patent.

Patented Sept. 7, 1915.

Application filed April 10, 1915. Serial No. 20,407.

To all whom it may concern:

Be it known that I, GEORGE W. GILL, a citizen of the United States, residing at Three Rivers, Michigan, have invented certain new and useful Improvements in Oilers for the Slides of Wind Musical Instruments, of which the following is a specification.

This invention relates to improvements in oilers for the slides of wind musical instruments.

My improvements are especially designed by me for use on trombones and I have illustrated my improvements embodied in such an instrument. My improvements may, however, be readily embodied in other instruments containing slides.

The main objects of my invention are to provide an improved oiler for slides of wind musical instruments which is effective in keeping the slide properly oiled and wiped free from dust.

A further object is to provide an improved oiler for the slides of wind musical instruments which can be readily applied to instruments now in use without material modification thereof.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Figure I is a detail side elevation of the slide portion of a trombone embodying my invention. Fig. II is an enlarged detail longitudinal section on a line corresponding to line 2-2 of Fig. I. Fig. III is an enlarged cross section on a line corresponding to line 3-3 of Fig. I. Fig. IV is a perspective view of one of the oiler sleeves removed from the instrument.

In the drawings, similar reference characters refer to similar parts throughout the several views, and the sectional views are taken looking in the direction of the little arrows at the ends of the section lines.

Referring to the drawings, 1 represents the outer or slide portion of a trombone, and 2 and 3 the coacting inner telescoping

members. The arms of the slide portion 1 are connected by a cross piece 4, while the members 2 and 3 are connected by the cross piece 5, as is the usual practice. The sleeves 6 are adapted to fit the inner ends of the slide member 1 and are longitudinally slotted at 7 to receive the cross piece 4. The sleeves project from the ends of the slide member 1 and are provided with annular enlargements 8 adapted to receive the lubricant retaining filler 9 so that it is supported to slidably embrace the inner telescoping members 2 and 3. This filler 9 is preferably a piece of wicking, as such material has considerable retaining capacity and is also well adapted to wipe dust from the inner members. The ends of the arms of the slide member 1 are preferably provided with lip-like extensions 10 which project into the chamber of the sleeve to engage and support the edge of the filler. A ring 11 is arranged in the outer end of the sleeve with its edge projecting into the chamber to provide a support lip 12 for the outer end of the filler. The filler is thus supported so that it cannot be accidentally disarranged, and it is also supported so that the inner telescoping members can be readily slipped through without disarranging the filler. The members 2 and 3 are provided with the usual stop collars 13 adapted to receive the buffers 14 with which the sleeves coat.

The device is not primarily intended as an attachment to be sold separate but to be embodied as a part of the instrument when manufactured. It may, however, be applied to an instrument already in use by shortening the slide the required amount before attaching the oiler, so that the combined slide and oiler would be the required length to give the proper tone in the first position.

My improvements are simple and economical to produce and may be used on various well known types of instruments.

The desired amount of lubricant is applied to secure the satisfactory results without an excess of lubricant, which is highly objectionable. Further, the parts are kept free from dust.

I have not attempted to illustrate or describe various adaptations or embodiments of my improvements as I believe the disclosure made will enable those skilled in the art to which my improvements relate to

embody or adapt the same as conditions may require. I desire, however, to be understood as claiming my improvements specifically in the form illustrated as well as broadly within the scope of the appended claims.

Having thus described my invention, what I claim as new and desire to secure by Letters Patent, is:

- 10 1. In a musical instrument of the class described, the combination of a pair of telescoping members, the outer slide member being provided with a cross piece at its inner end, a sleeve having an annular enlargement 15 providing an internal annular chamber, the inner end of said sleeve being fitted upon the outer slide member and longitudinally slotted to receive said cross piece thereof, whereby the sleeve is supported to slidably 20 embrace the inner member, a lip on the end of said outer slide member projecting into said chamber, a ring arranged in the outer end of said sleeve to project into said chamber to provide a filler supporting lip, and a 25 filler of wicking disposed in said chamber with its edges supported by said lips at the ends thereof.
2. In a musical instrument of the class described, the combination of a pair of telescoping members, the outer member constituting a slide member, a sleeve mounted upon the inner end of said slide member and having an annular enlargement providing an internal annular chamber, a lip on the 30 35 end of said slide member projecting into said chamber, a lip at the outer end of said sleeve projecting into said chamber, and a filler disposed in said chamber whereby said filler is supported to slidably embrace said inner member, said filler being adapted to receive a lubricant.
3. In a musical instrument of the class described, the combination of a pair of telescoping members, the outer member constituting a slide member, a sleeve mounted upon the inner end of said slide member and having an annular enlargement providing an in- 40 45

ternal annular chamber, a lip at the outer end of said sleeve projecting into said chamber, and a filler disposed in said chamber 50 with its edges supported by said lip whereby said filler is supported to slidably embrace said inner member, said filler being adapted to receive a lubricant.

4. In an instrument of the class described, 55 the combination of a pair of telescoping members, the outer member constituting a slide, a sleeve removably mounted on said outer member to project from the inner end thereof, said sleeve being provided with an internal annular chamber in its projecting portion having lips projecting into it at each end, and a filler disposed in said chamber with its edges engaged by said lips, said filler being adapted to receive a lubricant. 60 65

5. In an instrument of the class described, 70 the combination of a pair of telescoping members, the outer member constituting a slide, a sleeve removably mounted on said outer member to project from the inner end thereof, said sleeve being provided with an internal annular chamber in its projecting portion having a lip projecting into it, and a filler disposed in said chamber with its edge engaged by said lip, said filler being adapted 75 to receive a lubricant.

6. In an instrument of the class described, 80 the combination of a pair of telescoping members, the outer member constituting a slide, a sleeve removably mounted on said outer member to project from the inner end thereof, said sleeve being provided with an internal annular chamber in its projecting portion, and a filler disposed in said chamber and supported to slidably embrace the 85 inner telescoping member, said filler being adapted to receive a lubricant.

In witness whereof, I have hereunto set my hand and seal in the presence of two witnesses.

GEORGE W. GILL. [L.S.]
